UNITED STATES PATENT OFFICE.

LOUIS ROTHSCHILD, OF PHILADELPHIA, PENNSYLVANIA.

AUTO-TIRE CARRIER.

1,311,463.

Specification of Letters Patent. Patented July 29, 1919.

Application filed February 24, 1919. Serial No. 279,017

To all whom it may concern:

Be it known that I, LOUIS ROTHSCHILD, a citizen of the United States, residing at the city of Philadelphia, in the county of Philadelphia and State of Pennsylvania, have invented certain new and useful Improvements in Auto-Tire Carriers, of which the following is a specification.

My invention relates to a device for attachment to a motor-car body to clenchingly hold a plurality of tire-tubes, for ready use; and in such connection it relates to the constructive arrangement of the device for the defined purpose.

The principal objects of my invention are first, to provide an auto-tire carrier arranged to be readily assembled for use; second, to provide a device arranged to adjustably carry a plurality of tire-tubes, lockingly secured thereto; third, to provide a tire-tube carrier in which the members can be with facility adjusted to assume operative relation for reception of a plurality of tire-tubes; fourth to provide a tire-tube carrier having efficient means to unlock in part the device so as to release separately tire-tubes therefrom; fifth, to provide a tire-tube carrier, whereof an adjustable member serves also as a locking member by the shifting of the same to permit of the positioning of the others to assume such relation as to permit of the ready clenching and holding of the tire-tubes detachably applied thereto; and sixth, to provide a tire-tube carrier constructively arranged for reception of a plurality of tire-tubes in the manner substantially as hereinafter described.

The nature, scope and characteristic features of my present invention will be more fully understood from the following description taken in connection with the accompanying drawings forming part hereof, in which

Figure 1, is a front elevation view of the auto tire-tube carrier, embodying essential, main features of my invention.

Fig. 2, is a horizontal sectional view on the line 2-2, of Fig. 1.

Fig. 3, is a vertical sectional view on the line 3-3, of Fig. 1.

Fig. 4, is a fragmentary elevational detail view of the device, showing the locking member in a released or flexed position; and

Fig. 5, is a broken sectional view of the shiftable locking means with as part, a flanged cup-shaped sleeve to engage and

thereby lock the said nut in the tire carrying condition of said device.

Referring to the drawings *a*, represents the back of a motor-vehicle, and *a*¹, a gasoline tank suspended from beneath the car, *a*² and *a*³, represent two lower supporting brackets, and *a*⁴, an upper bracket projecting from the car body, as clearly illustrated in Figs. 2 and 3, and carrying at the free ends a flanged circular rim *a*⁵, adapted to be engaged by recessed shoes of the auto-tire tube carrier to be hereinafter fully explained.

The carrier consists as shown of a Y-shaped casting *b*, the two divergent arms *b*¹ and *b*², of which are threaded thereinto and at their opposite extremities are provided recessed shoes *b*³ and *b*⁴, arranged preferably in pairs for gripping the tire-tubes placed in contact therewith, as clearly shown in Figs. 1 and 3. The arms *b*¹ and *b*², are partially threaded at both ends, as shown in Fig. 1 so as to permit of the adjusting of both recessed shoes, in respect to the location of the central casting and also to enable the said carrier to be shipped, in a convenient knock-down condition, for ready assembling for application to a motor-car body, for use.

The middle section of the Y-shaped casting *b*, is internally arranged with a smooth surface throughout, as indicated in full outline in Fig. 5, for passing a threaded bolt *c*, therethrough. This bolt carries on its lower extremity a recessed gripping shoe *c*¹. The bolt *c*, is provided as shown, with a hexagonal-shaped nut *c*², to afford proper positioning of the carrier *b*, and also the jamming of the nut *c*², tightly against the lower end of the central section, of the Y-shaped casting *b*, as clearly shown in Figs. 3, 4 and 5. The threaded bolt *c*, is so arranged as to permit a cup-shaped sleeve member *d* to loosely travel thereon and to which member is pivoted a lever-arm *d*¹. This lever-arm in turn is pivoted to another lever-arm *d*², and at the lower extremity of the latter lever-arm is pivoted a tire-shoe *c*³, as clearly shown in Figs. 3 and 4, whereby through the shifting of the respective lever-arms *d*¹ and *d*², into the position, as shown in Fig. 3, the said sleeve is thereby elevated into a position to embrace and hence conceal the nut *c*², as clearly illustrated in Figs. 3 and 5 to prevent the said nut being turned; and at the same time the said lever-arms are presented so that the openings *d*⁴ and *d*⁵, register with each other to allow the tongue *f*¹, of the

padlock *f*, being passed therethrough, to securely lock the said lever-arms in contact with each other as in Figs. 1 and 3 and shown flexed in Fig. 4. In the position, as shown in Fig. 3, the tire-tubes *C*, *C*¹, are thereby securely held as shown in Figs. 2 and 3, against detachment, while the car is standing or on the road and is so held until said locking-means *f*, is released from the said lever-arms *d*¹ and *d*².

It will be observed that as the foregoing device is arranged, release of a tire-tube can be instantly accomplished, when the device is given the position, as shown in Fig. 4 and in this position, a tire tube can be replaced to assume a position to become locked thereto, as in Fig. 3, with at the same time the respective lever-arms *d*¹ and *d*², in overlapping contact position with each other.

It will be manifestly obvious that as to details in arrangement of the said device, modifications may be made, without departing from the spirit and scope of my invention; and therefore, I do not wish to be understood as limiting myself to the detailed arrangement of the same precisely as illustrated; but

Having thus described the nature and objects of my invention, what I claim as new and desire to secure by Letters Patent, is:—

1. An auto-tire tube carrier, comprising a member having arms carrying clencher-shoes, a bolt passing through said member and carrying a means to adjust said member in positioning said shoes, a sleeve movable on said bolt and carrying a lever arm, a clencher-shoe connected with the lower end of said bolt, a second lever-arm pivoted to said first-named lever arm and provided with a clencher-shoe in connection with the clencher-shoe of said bolt and a lock-means to engage said lever-arms in a certain position thereof, substantially as and for the purposes described.

2. An auto tire-tube carrier, comprising a

member having recessed shoes, a threaded vertical bolt passing through said member and having a recessed shoe and a lock-nut to adjust said member, in positioning said shoes, a sleeve loosely mounted on said bolt and having an extremity to embrace said nut, said sleeve pivoted to a lever-arm, a second lever-arm pivoted thereto and to a recessed shoe movably connected with said lever-arm and said shoe in turn pivoted to said bolt shoe and a lock-means to engage said lever-arms and registering with each other, substantially as and for the purposes described.

3. An auto-tire-tube carrier, comprising a tubular member having a plurality of adjustable extremital recessed gripping shoes, a vertical threaded bolt having a jam-nut and at the lower extremity carrying a fixed shoe, a shoe pivoted thereto, a sleeve loosely mounted on said bolt and having a flanged extremity to embrace said nut, lever-arms pivoted to each other and to said sleeve and one of said bolt-shoes and lock-means for said lever-arms, substantially as and for the purposes described.

4. An auto tire-tube carrier having recessed shoes, a central hollow member for reception of a bolt carrying a lock-nut, a sleeve with a flanged extremity arranged and operating to conceal said nut, said bolt carrying a fixed shoe and a complementary shoe pivoted thereto, lever-arms pivoted to said sleeve and to said last-named shoe and a lock-means for said lever-arms and arranged to engage the same, substantially as and for the purposes described.

In witness whereof I have hereunto set my signature in the presence of two subscribing witnesses.

LOUIS ROTHSCHILD.
